REFRIGERATOR CAR GUTTER
ARRANGEMENT

Victor E. West, New Kensington, Pa., assignor to
Standard Railway Equipment Manufacturing
Company, Chicago, Ill., a corporation of Dela-
ware

Application June 10, 1938, Serial No. 213,089

6 Claims. (Cl. 62—17)

The invention relates to refrigerator cars and more particularly to cars having the refrigerating means adjacent the top of the car. Refrigerator cars are used to transport perishable commodities and are insulated against outside temperatures and have a refrigerating means for use in summer and a heating means for use in winter. Means is also provided for the circulation of air to the lading from said heating and refrigerating means.

In a top bunker car, which is the name usually applied to a car having refrigerant containers adjacent the ceiling, there is a drip pan supported on an insulated partition below each container. These partitions serve two purposes: they catch and drain the melted refrigerant and they direct the circulating air in the intended direction. There are associated with the walls vertical flues leading downwardly from the passages just above said partitions. The melted ice and the circulating air flow through these flues from the refrigerant containers to the floor of the car where means are provided for draining the water to the outside of the car. The air then rises through the floor rack to the lading compartment.

The cold liquid formed by the melting refrigerant provides very good insulation for the sides of the car, as it flows through the flues. It is an object of this invention to place the gutter in the longitudinal center of the floor, thus using the liquid as a further insulation, as it flows over the floor from adjacent the walls to the center of the car.

As the warm air from the lading compartment reaches the refrigerant containers, the air is cooled by the heat absorbed in the melting of the refrigerant. When the air leaves the refrigerant containers it is still at a considerably higher temperature than the melted refrigerant which accompanies it on its flow over the partitions and down the flues. The air is further cooled by this contact with the liquid but very frequently it is warmer than the liquid when it reaches the floor of the car. It is a further object of this invention, by placing the gutter at the longitudinal center of the floor, to lower the temperature of the car by allowing the air to be further cooled by contact with the liquid as the liquid flows to the centrally located gutter.

It is a further object of the invention to position the stringers transversely of the car, thus keeping the melted refrigerant uniformly distributed over the floor and consequently improv-

ing the above mentioned insulating and refrigerating effects.

Another object of the invention is to slope the floor downwardly toward the gutter, thereby facilitating the flow of liquid on occasions when the car is not level.

It is a further object of the invention to reduce the number of gutters required, thereby reducing the initial cost, possibilities of leaks and the trouble caused by freezing and clogging of drains.

In the drawing:

Fig. 1 is a transverse section of a refrigerator car.

Fig. 2 is a section on line 2—2 of Fig. 1.

The usual parts of a refrigerator car are shown, such as center sill 2; side sills 3; cross members (bolster cross-beamer or cross tie) 4; a floor structure comprising sub-floor 5; stringers 6; floor 7; and insulation 15; walls comprising 20 sheathing 8; lining 9 and insulation 15; side plate 10, a roof structure comprising outside roof 11; ceiling 12 and insulation 15; ice containers 13 and hatches 14. Insulated partitions 20 are positioned below and spaced from each ice container 13 and are provided with drip pans on the upper surface thereof, otherwise made waterproof. Flues 21 lead from the passages 22 between the partitions 20 and ice containers 13 to adjacent the floor 7. The floor rack 23 comprises 30 a flat perforated sheet 24 preferably welded to a corrugated perforated sheet 25. The sheets 24—25 being supported above the floor 7 by transversely extending stringers 26 to provide a space 27 adjacent the floor.

A gutter 35 depressed below the top surface of the floor 7 is positioned at the center of the car and extends longitudinally thereof. The floor 7 is arranged to slope downwardly toward the gutter 35. The gutter is to be provided with 40 a sufficient number of water sealed drains 36 to drain the contents of the gutter to outside the car.

The construction shown herewith is intended to be used when the refrigerant is one that becomes liquid upon absorbing heat. Examples of this type of refrigerant are water ice, water ice mixed with salt and frozen brine known as eutectic ice.

The air circulation in the type of car illustrated is from the lading compartment 43, upwardly through the duct 41 and through the ice containers 13 where heat is absorbed by the melting refrigerant. The cooled air then flows downwardly through the flues 21 and into the 50

space 27 from whence it rises through the holes in the perforated plates 24-25 to the lading compartment 40. The melted ice falls through the foraminous walls of the refrigerant containers 13 onto the partitions 28, flows down the flues 21 to the floor of the car, and flows over the sloping floor 7 to the gutter 35 from where it is drained to outside the car.

The air, as it leaves the ice chambers 13, is at 10 a temperature considerably higher than that of the melted ice. Some heat is transferred as the air and liquid flow downwardly through the flues 21 but there is still a temperature differential when they reach the bottom. In the conventional car the gutters are placed immediately below the flues 21, therefore, any additional refrigerating effect remaining in the liquid when it reaches the bottom of the flues 21 is lost. When the gutter is at the center of the car the 15 air remains in contact with the liquid longer and, therefore, may absorb additional refrigeration before the liquid is drained from the car. Another advantage in having the liquid flow over the floor 7 is that the liquid provides additional insulation on the floor and reduces heat flow from the atmosphere to the inside of the car.

The products shipped in refrigerator cars are often loaded in containers in which the products 30 are marketed. It is, therefore, important that they are not soiled during transit. In the type of car shown, it is possible that liquid might be splashed from the gutter 35 through the openings in the foraminous floor 23, thus soiling the 35 lading. To prevent this means 42 are provided. The means 42 might comprise, for example, baffle plates secured to the stringers 26 above the gutter 35 but not in contact with the foraminous floor 23 so as not to restrict air flow through 40 the foraminous floor 23.

The floor rack stringers 26 extend transversely of the car. In addition to providing a free path for the circulation of air from the flues 21 this arrangement provides baffles to prevent the accumulation of liquid and cold air at one end of 45 the car due to the inertia of air and liquid when the car is in motion. Having the cold air in the space 27 at one end of the car is undesirable because the opposite end would have a deficiency of 50 refrigeration. The disadvantages of having the liquid accumulate at one end of the car are that it would be liable to flood that end of the car and that it would detract from the above mentioned benefits of having the liquid flowing over 55 the floor.

The drawing illustrates the gutter 35 positioned at approximately the center of the car. Any arrangement in which the gutter 35 is remote from the flue 21 to allow the air to remain 60 in contact with the liquid for a longer time is included within the scope of the invention.

Reference is herein made under rule 43 to my copending applications in which are disclosed certain constructions disclosed and claimed in 65 this application.

The accompanying drawing illustrates the preferred form of the invention, though it is to be understood that the invention is not limited to the exact details of construction shown and described, as it is obvious that various modifications thereof—within the scope of the claims—will occur to persons skilled in the art.

I claim:

1. In a refrigerator car having spaced apart 75 insulated walls, an insulated roof, an insulated

floor, and a foraminous floor spaced above the insulated floor to provide a space therebetween, in combination with an ice container near said roof and adjacent one of said walls, an insulated partition below said container and spaced therefrom to provide a substantially horizontal passage therebetween, a vertical flue associated with one of said walls and communicating between said passage and said space and a longitudinally extending gutter substantially at the center of the car and depressed below the top surface of said insulated floor, whereby melted ice from said container flows through said passage, flue and space into said gutter to further insulate said walls and floor.

2. In a refrigerator car having spaced apart insulated walls, an insulated roof, an insulated floor, and a foraminous floor spaced above the insulated floor to provide a space therebetween, in combination with an ice container near said roof and adjacent one of said walls, an insulated partition below said container and spaced therefrom to provide a substantially horizontal passage therebetween, a vertical flue associated with one of said walls and communicating between said passage and said space and a longitudinally extending gutter substantially at the center of the car and depressed below the top surface of said insulated floor, said insulated floor sloping downwardly toward said gutter, whereby melted ice from said container flows through said passage, flue and space into said gutter to further insulate said walls and floor.

3. In a refrigerator car having spaced apart insulated walls, an insulated roof, an insulated floor, and a foraminous floor spaced above the insulated floor to provide a space therebetween, in combination with an ice container near said roof and adjacent one of said walls, an insulated partition below said container and spaced therefrom to provide a substantially horizontal passage therebetween, a vertical flue associated with one of said walls and communicating between said passage and said space and a longitudinally extending gutter substantially at the center of the car and depressed below the top surface of said insulated floor, said gutter being provided with a water sealed drain leading to outside the car, whereby melted ice from said container flows through said passage, flue and space into said gutter to further insulate said walls and floor.

4. In a refrigerator car having spaced apart insulated walls, an insulated roof, an insulated floor, and a foraminous floor spaced above the insulated floor by transversely extending stringers resting upon said floor to provide a space therebetween, in combination with an ice container near said roof and adjacent one of said walls, an insulated partition below said container and spaced therefrom to provide a substantially horizontal passage therebetween, a vertical flue associated with one of said walls and communicating between said passage and said space and a longitudinally extending gutter substantially at the center of the car and depressed below the top surface of said insulated floor, whereby melted ice from said container flows through said passage, flue and space into said gutter to further insulate said walls and floor, and whereby said transversely extending stringers tend to keep said melted ice uniformly distributed upon said floor.

5. In a refrigerator car having spaced apart insulated walls, an insulated roof, an insulated floor, and a foraminous floor spaced above the

- insulated floor to provide a space therebetween, in combination with an ice container near said roof and adjacent one of said walls, an insulated partition below said container and spaced therefrom to provide a substantially horizontal passage therebetween, a vertical flue associated with one of said walls and communicating between said passage and said space and a longitudinally extending gutter remote from said flue and depressed below the top surface of said insulated floor, whereby melted ice from said container flows through said passage, flue and space into said gutter to further insulate said walls and floor.
- 5 6. In a refrigerator car having spaced apart insulated walls, an insulated roof, an insulated floor, and a foraminous floor spaced above the
- 10

insulated floor to provide a space therebetween, in combination with an ice container near said roof and adjacent one of said walls, an insulated partition below said container and spaced therefrom to provide a substantially horizontal passage therebetween, a vertical flue associated with one of said walls and communicating between said passage and said space, a longitudinally extending gutter substantially at the center of the car and disposed below the top surface of said insulated floor, and means to prevent liquid splashing from said gutter through said foraminous floor, whereby melted ice from said container flows through said passage, flue and space into said gutter to further insulate said walls and floor.
